FIG. 6

UNITED STATES PATENT OFFICE.

FREDERICK J. RIORDAN, OF LAWRENCE, MASSACHUSETTS, ASSIGNOR OF ONE-HALF TO
LAWRENCE SUGDEN, OF LAWRENCE, MASSACHUSETTS.

AMUSEMENT APPARATUS.

1,144,613.

Specification of Letters Patent. Patented June 29, 1915.

Application filed October 14, 1914. Serial No. 866,626.

To all whom it may concern:

Be it known that I, FREDERICK J. RIORDAN, a citizen of the United States, and resident of Lawrence, in the county of Essex and State of Massachusetts, have invented certain new and useful Improvements in Amusement Apparatus, of which the following is a specification.

This invention relates to coin-controlled apparatus capable of being used for amusement purposes.

The invention in the illustrated embodiment comprises a plurality of independently movable objects in the form of miniature automobiles, and independently operable mechanisms for said objects whereby they may be caused to traverse a race course. Each object and its operating mechanism is operated manually, and a plurality of persons each operating one of the units may cause the objects to engage in a speed contest.

Of the accompanying drawings, which illustrate the invention, Figure 1 represents a vertical section from front to rear through the apparatus. Fig. 2 represents a section through the structure indicated by line 2-2 of Fig. 1. Fig. 3 represents a top plan view, on a larger scale, of the two racing objects, the latter being indicated somewhat conventionally. Fig. 4 is a perspective view of a modification comprising means operable by a single coin for tripping a plurality of clutch devices to connect a plurality of racing objects with their respective operating members. Fig. 5 is a detail of the mechanism shown by Fig. 4. Fig. 6 represents a horizontal section of the mechanism shown by Fig. 2, the plane of the 40 section being between the racing surface and the operating mechanism. Fig. 7 represents a top plan view of disconnectible clutch mechanism by which motion is transmitted from one of the operating members 45 to the corresponding racing object. Fig. 8 represents a front elevation of the mechanism shown by Fig. 7. Fig. 9 represents an end elevation of the coin-operated mechanism included in Figs. 7 and 8.

The same reference characters indicate the same parts wherever they occur.

The apparatus as shown includes two racing objects in the form of automobiles, the

same being indicated at A, B. They are arranged to travel upon a raceway 15. A 55 is carried along the raceway by an endless chain 20^a, and B is carried by an endless chain 20^b. Chain 20^a is driven by a toothed sprocket wheel 21^a, and chain 20^b is driven by a similar sprocket wheel 21^b. Chain 20^a 60 coacts with an idle wheel 22^a which has a groove in its periphery to receive the chain. Chain 20^b coacts with an idle wheel 22^b which also has a groove in its periphery to receive the chain. As indicated by Fig. 6, 65 the course which is defined by the chains is substantially elliptic, and the raceway 15 is therefore provided with an elliptic slot 16 through which connection is made between the two objects A, B and their respective 70 chains. The form of connection for this purpose is shown by Figs. 1 and 3. A bar 23^a is affixed to one of the links of chain 20^a and extends upwardly through the slot 16, and to it is affixed the front axle 24^a of 75 A. A bar 23^b is affixed to one of the links of chain 20^b and extends upwardly through the slot 16, and to it is affixed the front axle 24^b of B. The body of A is pivotally connected by a kingbolt 25^a to the bolster 26^a 80 in which the front axle 24^a is journaled; and in like manner the body of B is pivotally connected by a kingbolt 25^b to the bolster 26^b in which the front axle 24^b is journaled. In consequence of this form of 85 connection the front axles of A and B are caused to turn to the required angle in rounding the ends of the racecourse, and are caused to be parallel to the rear axles when traversing the straight stretches of the 90 racecourse, to the end that the wheels of A and B may roll without skidding.

Drive wheel 21^a is affixed to a shaft 27^a, and idle wheel 22^b is loosely mounted upon said shaft. The drive wheel 21^b is affixed to a shaft 27^b, and idle wheel 22^a is loosely mounted on said shaft. Each idle wheel is thus free to rotate at a speed independent of the speed of the shaft upon which it is mounted, to the end that the speeds of A 100 and B shall be entirely independent of each other.

An operating member for A is indicated at 28^a in Fig. 6, and an operating member for B is indicated at 28^b in Figs. 1 and 6. 105 These operating members are in the form

of cranks and are affixed respectively to wheels 29^a and 29^b. 29^a is affixed to a shaft 30^a, and 29^b is affixed to a shaft 30^b.

The mechanisms for transmitting motion from the two operating members to their respective objects A and B are alike in all details, and a description of such mechanism for one of the units will be sufficient. The transmitting mechanism for A is shown in detail by Figs. 7, 8 and 4. Shaft 27^a is provided with a worm gear 31 which coacts with a worm 32. The worm is carried by a sleeve 33 which is loosely mounted upon shaft 30^a. Sleeve 33 constitutes one member of a disconnectible toothed clutch, being provided with teeth 34. The other member of the clutch is indicated at 35 and is arranged to slide longitudinally upon the shaft 30^a, being connected to the shaft by a spline 36. Sleeve 33 is provided with a ratchet wheel 37 which is engaged by a pawl 38 whose function is to prevent rotation in one direction. For this reason the clutch teeth are made in the form of ratchet teeth so that clutch member 35 will automatically back off from the sleeve 33 whenever the operating shaft is rotated in the wrong direction, and such rotation will not be imparted to the sleeve 33.

30 The clutch member 35 is otherwise disengaged from the sleeve 33 by mechanism which acts automatically when the racing object driven thereby has reached a predetermined point or traversed a predetermined distance. It may be here stated that according to the proportions illustrated three complete rotations of each sprocket wheel are required to cause one complete cycle of the corresponding chain, and the 40 above-mentioned mechanism which automatically disconnects the clutch acts only when the corresponding chain or racing object has traversed the racecourse three times. It will be understood, however, that these 45 proportions may be varied without departing from the spirit of the invention. It will also be understood that the course traversed by the racing objects may be circular, straight, or any other shape.

50 The sliding clutch member 35 is grooved to coact with a yoke or shipper 39. Said shipper is affixed to a rockshaft 40 which is provided with a weighted arm 41 whose function is to hold the clutch member 35 55 normally in coercive engagement with the teeth of sleeve 33. As shown by Fig. 7, the clutch member 35 is retracted, and the weighted arm 41 is lifted to the position indicated by solid lines in Fig. 9. For the 60 purpose of disconnecting the clutch, the said shaft is provided with an arm 42. One end of a link 43 is pivotally connected to the free end of arm 42. This link has on its lower edge a shoulder 65 44 which is arranged to be engaged by a

finger 45 of a star wheel 46. A stud 47 carried by the worm gear 31 coacts with the star wheel to turn the latter intermittently in the direction indicated by an arrow in Fig. 7. The star wheel has nine points, including the finger 45. As it requires three rotations of shaft 27^a to cause one complete lap of the racing object, the provision of nine points on the star wheel causes the latter to make one complete rotation while the racing object is traversing three laps. Assuming, therefore, that the link 43 is in the position indicated by solid lines in Fig. 9, the shoulder 44 at such time being in the plane of the finger 45, the latter will strike the shoulder 44 when the racing object has completed three laps, and in consequence of such engagement the rockshaft 40 will be actuated to retract clutch member 35. Continued rotation of shaft 30^a will not be transmitted to the racing object until the link 43 has been disengaged from the finger 45, so that the weighted arm 41 may throw the clutch member 35 into engagement with clutch teeth 34.

The operation of connecting the clutch is performed by coin-controlled mechanism now about to be described. As shown by Figs. 1 and 9, the free end of link 43 is connected to a rod 48. The lower end of the rod is arranged to slide up and down in a fixed guide 49. A lever 50 is arranged to lift the rod 48 in consequence of dropping a coin in the coin chute hereinafter described. The lever 50 is mounted upon a fulcrum 51 and is provided with a plate 52 upon which the coins drop, the weight and momentum of the coin being sufficient to lift the rod 48 so as to raise the link 43 to the position indicated by dotted lines in Fig. 9. When the link is so lifted, the shoulder 44 is disengaged from finger 45, whereupon the weighted arm 41 drops to the position indicated by dotted lines, thereby swinging the arm 42 to the right until the clutch is connected. As soon as the coin drops from the plate 52, the rod 48 and link 43 drop until the shoulder 44 rests upon the top of the finger 45. When the finger 45 is removed in consequence of operating the shaft 30^a, it ceases to support the link 43, whereupon the link and rod 48 drop to the positions indicated in Fig. 9 at 43^x and 48^x, which positions are determined by guide 49 and a collar 49^x affixed to 48. The shoulder 44 is thus returned to the plane traversed by the finger 45, to be subsequently engaged and moved to the left by the finger when it has completed one rotation.

Duplicate coin chutes 53 are shown in Fig. 6, and one of them is shown in Fig. 1. Each chute is supported by a bar 55. Coins may be inserted into the upper ends of the chute through slots (not shown) in the raceway 15. The lower end of each chute reg-

isters with a coin-receiving opening 61 in a box 58, the corresponding lever 50 being arranged in and supported by said box so that the coin entering through 61 will drop upon plate 52. The coin eventually drops into a pan 60 in the box. The box has a door 59 which is provided with a lock 65, the bolt of which coacts with a plate 66. The box rests upon a support 63 and its position in the cabinet C is determined by a stop 64 which causes the lever 50 to register with the rod 48.

The apparatus is mounted in a case or cabinet C the front side of which is provided with a door C' which affords access to the interior.

The arrangement of the coin-actuated mechanism may be varied. For example, as shown by Fig. 1 the coin chute, lever 50 and rod 48 are arranged to control but one of the clutches, namely, that which drives B. A similar chute, coin receptacle, lever and lifting rod may be provided for the clutch which drives A, to the end that a coin must be deposited in each of the chutes in order to render both of the racing objects capable of participating in a race. I have contemplated another arrangement, whereby both driving clutches may be set in operation by the deposit of a single coin. Mechanism such as that shown by Figs. 4 and 5 is suitable for the latter purpose. In these figures the links indicated at 43^a, 43^b answer the same purpose as the link 43 shown in Figs. 1, 7 and 9. There is one difference, however, which is that the shoulders 44^a 44^b, which serve the same purpose as the shoulder 44, are formed on the upper edge of the links instead of on the lower edge, necessitating a downward movement of the free ends of the links in order to set the clutches in operative position. The free end of link 43^a extends loosely through a hole formed in a lever 67, and in like manner the free end of link 43^b extends loosely through a hole formed in a lever 68. The fulcrum or pivot of 67 is indicated at 69, and that of 68 is indicated at 70, the said levers extending toward and overlapping each other and being connected at 71 by any suitable connection, such as a pin-and-slot connection, adapted to cause the levers to operate in unison. One of the levers, in the present instance 67, is provided with a hole through which the upper end of the rod 72 is hooked. The rod 72 is, to all intents and purposes, the equivalent of rod 48, and, when combined with a lever such as that indicated at 50, will be lifted by the deposit of a coin in the manner hereinbefore explained. Upward movement of rod 72 causes downward movement of the free ends of links 43^a and 43^b, the shoulders 44^a and 44^b being thereby moved sufficiently to be disengaged from the star wheels with which they coact.

When the driving clutches are connected, motion of the operating members is transmitted positively to the respective racing objects, and the speeds of the racing objects are determined by their respective operating members. The racing object which is the first to reach the finish line at the completion of three (in the present instance) laps, is the first to be disconnected from its operating member; and the other racing object may continue to travel until it reaches the finish line after having completed three laps, whereupon its clutch will be automatically disconnected. The racing objects are thus left abreast of each other in the desired position for the start of the next race.

I claim:—

1. An apparatus of the character described, comprising an endless racecourse, an object arranged to traverse said course, an operating member, means arranged to transmit motion from said operating member to drive said object along said course, and means arranged to act upon said transmitting means automatically to disconnect said object from said operating member when said object has traversed a predetermined plurality of laps around said course.

2. An apparatus of the character described, comprising a movable object, an operating member, means arranged to transmit motion from said operating member to drive said object, and means driven by said operating member and arranged to adjust said transmitting means automatically to disconnect said object from said operating member when said object has traveled a predetermined distance.

3. In an apparatus of the character described, a racecourse, a wheeled vehicle arranged to roll upon said course, said vehicle having a swiveled steering truck, and means arranged to pull said vehicle, said means being connected to said truck to turn the same laterally to steer the vehicle.

4. An apparatus of the character described, comprising a movable object, an operating member, means arranged to transmit motion from said operating member to cause said object to travel an endless course, said transmission means including disconnectible clutch members, and means arranged to disconnect said clutch members when said object has traversed a predetermined plurality of laps of said course.

5. An apparatus of the character described, comprising a movable object, an operating member, means arranged to transmit motion from said operating member to cause said object to travel an endless course, said means including disconnectible clutch members, and means driven by the driven clutch member arranged to disconnect said clutch members when said object has traversed a predetermined plurality of laps of said course.

6. An apparatus of the character described, comprising a movable object, an operating member, means arranged to transmit motion from said operating member to cause said object to travel an endless course, said means including disconnectible clutch members, intermittent gearing arranged to be driven by said transmission means, and means arranged to be operated by said intermittent gearing to disconnect said clutch members when said object has traversed a predetermined plurality of laps of said course.

7. An apparatus of the character described, comprising a movable object, an operating member, means arranged to transmit motion from said operating member to cause said object to travel, said means including disconnectible clutch members, yielding means arranged to hold said clutch members connected, and means arranged to be actuated by said transmission means to disconnect said clutch members against the force of said yielding means when said object has

traversed a predetermined distance, said disconnecting means including a trip member arranged to release said yielding means.

8. An apparatus of the character described, comprising a plurality of independently operable groups of mechanism each including a movable object, an operating member, means arranged to transmit motion from said operating member to drive said object, and means arranged to adjust said transmitting means automatically to disconnect said object from said operating member, said disconnecting means including a trip member; and controlling means arranged to displace the several trip members to connect said objects with their respective operating members.

In testimony whereof I have affixed my signature, in presence of two witnesses.

FREDERICK J. RIORDAN.
